UNITED STATES PATENT OFFICE

ABRAHAM M. DELLINGER, OF LANCASTER, PENNSYLVANIA

HAMMER-MILL ROTOR

Application filed October 29, 1928. Serial No. 315,816.

This invention relates to rotors for hammer type feed mills such as now extensively used on farms and elsewhere for grinding suitable farm produce, including grains generally and their stems, vines etc. and hay for preparing ground feeds, ensilage and the like for stock, poultry etc. and for similar grinding purposes generally.

The primary objects of the present invention are, to provide a simple, quickly assembled, and positive means for locking the supporting hammer spacing discs in proper relation to each other and prevent their working loose during operation; to provide a construction wherein the said discs are positively locked against peripheral movement relative to the shaft of the rotor; to provide a locking means thrusting in an axial direction against said supporting discs and itself held by said axial thrust against relative movement in a peripheral direction relative to the shaft; to avoid the action of all peripheral creeping action of the discs on the locking means; to provide supplementary adjustable rotary means for adjusting the axial relation of the discs of the gang of supporting discs with relation to each other while protecting said supplemental means against all peripheral creeping action of said discs with relation to the shaft and said supplemental means; to provide a very compact, efficient, quickly assembled positively locked rotor construction without interfering with the ease of insertion, adjustment or removal of the individual relatively swinging hammers carried in a rotary path by said rotor; to provide a construction wherein the expensive operations of successively turning down the shaft to provide an end stop shoulder, a smaller disc carrying portion, a smaller threaded portion for the locking nuts etc. are avoided; to provide a construction wherein the shaft and stop-collars or stop collar and locking means are made as separate parts, but as assembled the collars are positively interlocked with integral projecting parts of the shaft in such manner as to prevent all relative turning movement between said parts; and to provide a rotor economical of manufacture and peculiarly lending

itself to manufacture on a large production basis, all as hereinafter more particularly set forth, described and claimed.

In this application I show and describe only the preferred embodiment of my invention simply by way of illustration of the practice of my invention as by law required. However, I realize that my said invention is capable of other and different embodiments and that the various details thereof may be modified in different ways. Therefore, the drawing and description herein are to be considered as merely illustrative and not as exclusive.

In the accompanying drawing:

Figure 1 represents a longitudinal central sectional view through a rotor embodying my invention, the shaft thereof being shown in elevation;

Figure 2, a sectional view on the line 2—2 of Fig. 1, looking in the direction of the arrows, the end disc 4 being broken away;

Figure 3, a fragmentary detail perspective view of one end portion of the shaft showing the locking collar 3' in the course of being applied thereto;

Figure 4, a sectional view on the line 4—4 of Fig. 2; and

Figure 5, a sectional view on the line 5—5 of Fig. 1, the disc 4 through which it is in part taken being broken away.

Referring now in detail to the drawings, 1 designates the usual cylindrical end portions of the rotor shaft, which is formed with a long medial portion 5 angular in cross-section, being preferably square as shown, and being of suitable length to receive the hammer spacing discs 4 with their intervening spacing and clamping collars 6, the total length of the combined thicknesses of said discs 4 and spacing collars 6 interposed between them being preferably substantially equal to, or slightly in excess of the length of said angular portion 5 and composing the operative hammer grinding portion of the rotor which may be made in different lengths to suit different sizes of mills and operative power plants therefor.

Between the respective cylindrical end portions 1 and the adjacent end portions re-

spectively of the angular portion 5 an angular flange 3 or equivalent having sharp angular portions *a* or radial projections is provided, the inner faces of each of the flanges 3, that is, the faces thereof presented toward 5 the portion 5, or of the projections *a* making up the same, all lying preferably substantially in the same plane perpendicular to, and transversely of, the axis of portion 5, said flanges 3 respectively being spaced from 10 the respective ends of the portion 5 by cylindrical portions 7 respectively, said sections 7 preferably being of the same diameter as the cylindrical end portions 1. The flanges 1 or the abrupt radial projections *a* thereof, 15 or equivalents, will preferably be integral with the shaft portion 5, as will preferably also the end portions 1 and cylindrical portions 7. However, it is not essential that the flanges 1 or abrupt projections *a* thereof, 20 or equivalents shall be integral with shaft portions 1, 7 and 5, and they may be constructed otherwise.

In practice the shaft comprised of the portions 1, 3, 5 and 7 will usually and preferably 25 be produced by taking a piece of steel angular in cross-section, preferably square, and of the proper length and cross-sectional size, turning down its end portions to form the cylindrical portions 1, smoothing up the faces of 30 the intervening portion as may be necessary or as may be preferred, and then turning down portions respectively adjacent the respective ends of the remaining square portion, so as to form the cylindrical portions 7 respectively between the respective ends of angular portion 5 and the respective flanges 3. Preferably, as shown, the cylindrical portions 35 7 will be of the same diameter and axial length to form annular grooves of the same width, in an axial direction, between the respective flanges 3 and the respective adjacent ends of the medial angular portion 5.

Two collars 9 and 9' respectively are applied to the respective ends of the shaft and 40 moved axially thereof toward the respective flanges 3 and over said flanges 3 into the annular grooves between said flanges 3 respectively and the respective adjacent ends of the angular portion 5 so as to extend about the cylindrical portions 7 respectively. Said collars 9 and 9' will be respectively of such thickness as to make a tight fit in said grooves between the opposed faces of the respective flanges 3 and adjacent ends of the angular portion 5 to such extent preferably that some appreciable twisting force is necessary to 45 partially turn said collars about the axis of portions 7 respectively.

Said collars 9 and 9' respectively will be 50 formed with central openings of the same cross-sectional shape as the cross-sectional shape of the respective flanges 3, preferably square, as shown, and of such size as to just slip over the respective flanges 3. The said.

collars 9 and 9' will in all respects be duplicates of each other, except that collar 9' will have two diametrically opposite axially extending screw-threaded bores extending through it to receive locking end-thrust screws 11 respectively, whereas collar 9 need not have, and said collars will have recesses *b* with abrupt radially extending walls formed in their distant outer faces, said recesses communicating with the central opening of their respective collars, preferably being located equi-distantly between the corners of said openings and extending a substantial distance axially of their respective collars, and being of such size and shape as to receive their respective cooperating radially extending angular projections *a* of their respective flanges 3.

The discs 4 and the collars or spacing elements or rings 6 will have central openings corresponding in shape to the cross-sectional shape of the portion 5 and of such size as to make a snug fit thereon, as shown in Figure 5, though it is not essential that the spacing elements or blocks 6 shall have such angular central openings, though it is preferable.

The discs 4 will be perforated at intervals in a peripheral direction and as assembled will have their perforations in axial alignment to receive a plurality of axially extending pins or tie rods 8 secured in position by means of cotter pins or other suitable means 10 passing through their respective end portions beyond the respective end discs 4, said pins 8 passing through and serving to pivotally mount one or more hammers each between a pair of discs 4, said hammers 12 respectively being of the same thickness preferably as the spacing elements 6 and being mounted one or more on each of the tie-rods or pins 8 and being disposed at different points axially and peripherally of the assembled discs, the relative arrangement of said hammers 12 being as may be desired and in accordance with the usual practice in the art, the said hammers being free to swing about said pins or tie rods on coming into contact with some object fed into the rotor, all as usual.

To assemble, the thrust or adjusting or locking screws 11 will be turned into their respective bores in locking collar 9' and locking nuts 13 will be turned on their inner ends respectively, but not into locking engagement with the opposed inner face of the collar 9'. The collar 9, serving as a stop collar, will be applied over its corresponding end of the shaft and moved axially thereof until received in its corresponding groove between its cooperating flange 3 and the adjacent end of angular portion 5, when it will be partially rotated until its recesses *b* are in axial registry with the projections *a* of said flange 3, when it will be moved in the reverse axial direction until the opposed axial faces

of said projections *a* of said flange 3 are in engagement with the axial walls respectively of said recesses *b* of said collar 9, when said projections *a* will preferably be welded in said recesses *b*, thus making said collar 9 operatively integral with the shaft.

The discs 4 with their spacing elements 6 are then alternately applied over the other end portion of the shaft and moved to the 10 angular portion 5 thereof and when all of said discs and spacing elements have been thus applied, the locking collar 9' is moved into proper position, in the manner described with relation to collar 9, partially rotated 15 until its recesses *b* are in axial alignment with the corresponding projections *a* of its flange 3 and then moved in the reverse axial direction so that its said recesses *b* respectively receive the respective cooperating projections *a* 20 of its cooperating flange 3, when the said screws 11 will be screwed in to bear against the adjacent end of the gang of discs 4 and spacing blocks 6 to force the same in an axial direction tightly together in opposition to the 25 collar 9 and to force the collar 9' axially in the reverse direction to force the recesses *b* of its collar 9' completely on the respective projections *a* in an axial direction and to take up all slack, and when said screws 11 have 30 thus been properly adjusted the respective locking nuts 13 will be turned up on said screws 11 respectively into tight locking engagement with the opposed face of said collar 9', when the assembling operation will be 35 complete. If at any time due to use the parts loosen up a little, due to possible wear, so that there is end play of the discs 4 this may be taken up by loosening the nuts 13 and properly readjusting the screws 11, and 40 thereafter turning the nuts 13 to lock their respective screws 11 in such adjusted positions, and to facilitate such adjustment of the screws 11 they may be formed with angular sockets in their outer ends to receive an 45 angularly headed wrench such as now well known.

Any suitable material may be used for any part, though I prefer to use malleable iron castings for the collars 9 and 9' and sheet metal stampings for the discs 4 and while it is preferred that the collar 9 shall be welded to the flange 3 cooperating with it, this is not essential as by the thrust of the 50 screws 11 on the other end of the gang of discs 4 and elements 6 the collar 9 would be forced axially with relation to the cooperating flange 3 so as to retain the projections of said flange in the corresponding recesses *b* of said collar 9, thus effectually preventing partial rotary relative movement such as would be necessary before there could be any relative axial movement between the collar 9 and the shaft.

Having thus described my invention, what

I claim as new and desire to secure by Letters Patent is:

1. A hammer-mill rotor comprising a rotary shaft having a medial portion non-circular in cross-section, and two radially extending portions respectively axially spaced from the respective end portions of said medial portion, in combination with a plurality of discs, means extending through said discs for pivotally mounting the usual hammers, and retaining means respectively fitting between the respective radially extending portions and the respective adjacent end portions of said medial portion and respectively in interlocking engagement with their said radially extending portions, said retaining means between them confining said discs to the medial portion of the shaft, said discs respectively having central openings corresponding in shape and size to the cross-sectional shape and size of said shaft medial portion and making a tight snug fit thereon.

2. A hammer-mill rotor comprising a rotary shaft having a medial portion non-circular in cross-section, and two radially extending portions equidistantly axially spaced from the respective end portions of said medial portion, in combination with a plurality of discs, means extending through said discs for pivotally mounting the usual hammers, and retaining means respectively fitting between the respectively radially extending portions and the respective adjacent end portions of said medial portion and respectively axially interlocking with their said radially extending portions to prevent rotary movement of said retaining means relative to their cooperating radially extending portions, said retaining means between them confining said discs to the medial portion of the shaft, and said discs respectively having central openings corresponding in shape and size to the cross-sectional shape and size of said shaft medial portion and making a tight snug fit thereon.

3. A hammer-mill rotor comprising a rotary shaft having a medial portion and two flanges having abrupt radially extending faces, the respective opposed faces of which lie in the same transverse plane perpendicular to the axis of said shaft, said flanges respectively being spaced axially from the respective end portions of said medial portion and respectively separated therefrom by annular grooves, in combination with a hammer-carrying unit mounted on said medial portion of said shaft and positively held thereon against relative rotary movement, closed retaining collars respectively having central openings corresponding in shape and size to their respective flanges and being of such thickness as to make a tight fit in their respective grooves, said retaining collars fitting in said grooves respectively and having their outer faces respectively formed with radially

disposed recesses having sharp abrupt radially and axially extending walls and corresponding in shape and size to, and snugly receiving, the respective radial projections of their respective cooperating flanges, and means mounted in one of said collars for axial adjustment to thrust against said hammer-carrying unit and with the same cooperating to force said collars in opposite axial directions and maintain said collars in interlocked relation with their respective flanges, preventing relative rotary movement between said collars and their respective cooperating flanges.

4. A hammer-mill rotor comprising a rotary shaft having a medial portion non-circular in cross-section, a radially extending stop adjacent one end of said medial portion and immovable relative thereto, and a flange adjacent the other end thereof and immovable with relation to said shaft, in combination with a plurality of spaced discs mounted on the medial portion of said shaft and respectively having central openings corresponding in shape and size to the cross-sectional shape and size of said medial portion of the shaft and making a tight fit thereon to prevent relative rotary motion between said shaft and each of said discs, a closed collar having a central opening corresponding in size and shape to said flange and fitting between said flange and the opposed end of said plurality of discs, said collar being formed to axially overlap and interlock with said flange against relative rotary movement, and adjustable means carried by said collar and being adjustable to engage the adjacent end of said plurality of discs to force said discs axially toward each other and to force said discs as a unit axially against said stop and to force said collar in the reverse axial direction into full overlapping interlocking engagement with said flange.

5. A hammer-mill rotor comprising a rotary shaft having a medial portion non-circular in cross-section, a radially extending stop adjacent one end of said medial portion and operatively immovable with relation thereto, and a flange adjacent the other end thereof and operatively relatively immovable, in combination with a plurality of spaced discs mounted on the medial portion of said shaft and respectively having central openings corresponding in size and shape to the cross-sectional size and shape of said medial portion of said shaft and making a snug fit thereon, an element disposed about said shaft between said flange and medial portion and interlocking with said flange against rotary motion relative thereto, and adjustable means carried by said element and operable to force said plurality of discs as a unit axially into tight engagement with said stop and said element in the reverse axial direction into tight interlocking engagement with said

flange and to maintain said parts in such relation.

6. A hammer-mill rotor comprising a shaft having a medial portion non-circular in cross-section, and two flanges respectively equidistantly axially spaced by annular grooves respectively from the respective end portions of said medial portion, said medial portion and said flanges being integral and said flanges being of the same cross-sectional size and shape as said medial portion, in combination with two closed collars respectively fitting in said grooves and having their axially outer faces recessed to partially receive said flanges in axially overlapping relation, said collars each having two abrupt axially extending eccentric walls and an axially inner radially extending wall engaging correspondingly shaped faces on the respective flanges, a plurality of discs mounted on said shaft medial portion and respectively having central openings corresponding in size and shape to the cross-sectional size and shape of said shaft medial portion and making a tight fit thereon, means interposed between said discs to together with said discs constitute a spaced disc hammer carrying unit, and adjustable means mounted in one of said collars and bearing on the adjacent end of said built up hammer carrying unit and operable to, together with said unit, exert an axial thrust on said collars to hold them in interlocking engagement with their respective flanges.

7. A hammer-mill rotor comprising a shaft having a medial portion non-circular in cross-section, and two flanges respectively equidistantly axially spaced by annular grooves respectively from the respective end portions of said medial portion, said medial portion and said flanges being integral and said flanges being of the same cross-sectional size and shape as said medial portion, in combination with two closed collars respectively fitting in said grooves and having their axially outer faces partially recessed to partially receive said flanges in axially overlapping relation, said collars each having two abrupt axially extending eccentric walls and a radially extending axially inner wall, said walls engaging correspondingly shaped faces on the respective flanges, a plurality of discs mounted on said shaft medial portion and respectively having central openings of the same size and shape as the cross-sectional size and shape of said medial portion of said shaft to make a tight fit thereon, means interposed between said discs to together with said discs constitute a spaced-disc hammer-carrying unit, one of said collars being permanently rigidly connected with said shaft, and adjustable means mounted in the other of said collars and bearing on the adjacent end of said unit and operable to force the discs and spacing means therefor axially into tight clamping relation and the unit as

a whole axially into tight engagement with said permanently mounted collar and to force the collar in which said adjustable means are mounted in the reverse axial direction into tight interlocking engagement with its flange.

8. A hammer-mill rotor comprising a shaft having a medial portion non-circular in cross-section, and two flanges respectively 19 equidistantly axially spaced by annular grooves respectively from the respective end portions of said medial portion, said medial portion and said flanges being integral and said flanges being of the same cross-sectional 15 size and shape as said medial portion, in combination with two closed collars respectively fitting in said grooves and having their axially outer faces recessed to partially receive said flanges in axially overlapping relation, said collars respectively having two 20 abrupt axially extending eccentric walls and an axially inner radially extending wall, said walls of the respective collars engaging corresponding faces of the respective flanges, a plurality of discs mounted on said shaft medial portion and respectively having central openings of the same size and shape as the cross-sectional size and shape of said medial portion of said shaft to make a tight 25 fit thereon, means interposed between said discs to together with said discs constitute a spaced-disc hammer-carrying unit, one of said collars being welded to its cooperating flange, and axially adjustable screws working 30 in diametrically oppositely disposed internally screw-threaded axially extending bores in the other of said collars and individually adjustable therein to thrust against the adjacent end of said disc unit.

9. A hammer-mill rotor comprising a shaft having a medial portion non-circular in cross-section, and two flanges respectively 40 axially spaced by annular grooves respectively from the respective end portions of said medial portion, said medial portion and said flanges being integral and said flanges being of the same cross-sectional size and shape as said medial portion, in combination with two closed collars respectively fitting in said 45 grooves and having their axially outer faces recessed to partially receive said flanges in axially overlapping relation, said collars each having two abrupt axially extending eccentric walls and an axially inner radially 50 extending wall, said walls of the respective collars engaging corresponding faces of the respective flanges, a plurality of discs mounted on said shaft medial portion and respectively having central openings of the 55 same size and shape as the cross-sectional size and shape of said medial portion of said shaft to make a tight fit thereon, means interposed between said discs to together therewith constitute a spaced-disc hammer- 60 carrying unit, one of said collars being

permanently rigidly connected to its cooperating flange, axially adjustable screws working in diametrically oppositely disposed axially extending bores in the other of said collars and individually adjustable 70 therein to thrust against the adjacent end of said unit, and locking nuts respectively applied to the respective screws between said unit and the collar in which said screws are mounted and cooperating with said collar to lock their respective screws in adjusted 75 position.

10. A hammer-mill rotor comprising a rotary shaft having a medial portion non-circular in cross-section, a radially extending stop adjacent one end of said medial portion and operatively immovable with relation thereto, and a flange adjacent the other end thereof and operatively relatively immovable, in combination with a plurality of 80 spaced discs mounted on the medial portion of said shaft, a plurality of spacing blocks mounted on the medial portion of said shaft, said blocks and discs each having a central opening corresponding in size and shape to the cross-sectional shape of said medial portion of the shaft and making a snug fit thereon, and said blocks and discs being arranged in alternation to together constitute a spaced-disc hammer-carrying unit, an element disposed about said shaft between said flange and the adjacent end of said unit and interlocking axially with said flange against rotary motion relative thereto and means carried by said element and engaging the adjacent end of said unit at diametrically opposite points and operable to force said discs and blocks comprising said unit axially into tight clamping engagement and to force said unit as a whole axially into tight engagement with said stop and said element in the reverse axial direction into tight axially overlapping interlocking engagement with said flange and to maintain said parts in such relation.

In testimony whereof, I have signed my name to this specification at Lancaster, Pennsylvania this 26th day of October, 1928.

ABRAHAM M. DELLINGER.
